S. J. VESELY

SHOCK ABSORBER

Filed Jan. 27, 1922

Inventor
Stanley J. Vesely
By J. M. C. John
Atty.

UNITED STATES PATENT OFFICE.

STANLEY J. VESELY, OF CEDAR RAPIDS, IOWA.

SHOCK ABSORBER.

Application filed January 27, 1922. Serial No. 532,288.

To all whom it may concern:

Be it known that I, STANLEY J. VESELY, a citizen of the United States, residing at Cedar Rapids, in the county of Linn and State of Iowa, have invented certain new and useful Improvements in Shock Absorbers; and I do hereby declare the following to be a full, clear, and exact description of the invention, such as will enable others skilled 10 in the art to which it appertains to make and use the same.

This invention relates to shock-absorbers for motor vehicles in which the body springs are mounted parallel with the axles, and 15 embodies certain improvements in the type of shock-absorbers for which Letters Patent were issued to me on the twelfth day of July, 1921, No. 1,384,545.

The object of this invention is to simplify 20 the construction of the shock-absorber, more especially in the hanging of the body spring thereon, with a view to economy in manufacture and improvement in the riding quality.

The invention is fully disclosed in the description and claim following, reference being had to the accompanying drawing, in which:

Fig. 1 is an elevation of my improved device as applied to the rear axle of an automobile of familiar make, and as seen from a point at right angles to the axle. Fig. 2 is a section of the same, in the line 2—2 of Fig. 1, looking toward the left.

In the drawing the numeral 5 denotes the 35 rear axle housing of an automobile, with a brake-member 6 at the end thereof. To this is bolted a post 7, which serves as a support for one end of the body spring 8 through a lever 9 forming a part of the shock-absorber. 40 The lever is provided with a depending lug 10, in which is formed a recess 11 to receive the eye 12 of the leaf spring, and serving as a seat therefor. The eye of the spring is held in place by a cross-pin or bolt 13. To 45 the axle is clipped a pair of spring-barrels 14, of substantially the same construction as described in the patent above referred to. In this case, however, the bolts 15 are secured to the lower washers 17, and do not change 50 position with the movement of the parts above. On the bolts, near their upper ends, is loosely mounted a yoke 18, arched in the middle to give clearance for the leaf spring, and provided above with lugs 19 to engage 55 the longer arm 20 of the lever above referred to, by a cross-bolt 21. The parts 22 of the

yoke, which rest on the upper washers, and in the loading or jolting of the body compress the interposed coil springs 23, are rounded on their washer-engaging faces, 60 since it is evident that the yoke must rock a little as it moves up and down. It is to be noted also that the spring-barrels are set at a little inclination to the axle, so as to approximate the arc of movement described by 65 the lever at its connection with the yoke, and thereby limit the rocking action of the latter.

The construction avoids the necessity of using a linked connection of the leaf spring with the lever of the shock-absorber, since 70 the outward and downward movement of the leaf-spring supporting pocket corresponds with the natural movement of the eye of the leaf spring, as the latter straightens and extends under superimposed pressure. It also tends to prevent swinging of the vehicle body sidewise, since the leaf spring cannot swing in this direction except as it is forced downwardly, or rebounds upwardly. The pocket for the end of the leaf 75 spring serves also as grease-cup for continued lubrication of the spring and its pivot-bolt at this point.

The improved mounting of the yoke permits it to move more freely up and down 80 than if rigidly secured to the vertical bolts and in its capacity as a link gives perfect freedom of movement to the lever of the shock-absorber. At the same time it is held 85 in operative contact with the coil springs, and forces them to yield both on the downward pressure and the upward rebound, thus softening and modifying the jolts and jars brought to bear on the leaf spring.

Instead of playing up and down in the 90 barrels, and projecting below them in such movement, the bolts do not move, except when there is a high rebound. The improved device presents a better appearance, while in use, and is also safer, since there 95 was always the possibility of the bolts, in their downward movement, catching on some upstanding obstruction in the road, a stone or stump, and so causing trouble, if not more or less serious damage.

Having thus described my invention, I claim:

In combination with an axle and supporting post, a leaf spring lever pivoted to the post, and having a depending, rigid member to engage the spring-eye pivotally, coil-spring supporting barrels disposed on each 110

side of the axle, a yoke playing up and down therein, connecting with the free end of the lever pivotally, its lateral arms being rounded below, and pierced to receive spring-bolts loosely, coil springs seated in said barrels, the barrels being inwardly flanged to retain their ends, bolts passing through the springs and loosely through the yoke-arms, and washers secured to the opposite ends of the

bolts, whereby the bolts remain stationary ¹⁰ except in the extreme upward rebound of the yokes.

In testimony whereof I affix my signature in presence of two witnesses.

STANLEY J. VESELY.
